H. G. BARRETT

SHAFT FOR GOLF CLUBS AND THE LIKE

Filed Nov. 7, 1925

By *J. E. Johnson Jr.*
Inventor
Harold G. Barrett

UNITED STATES PATENT OFFICE.

HAROLD G. BARRETT, OF WILMETTE, ILLINOIS, ASSIGNOR TO BARBARITE CORPORATION, OF CHICAGO, ILLINOIS, A CORPORATION OF ILLINOIS.

SHAFT FOR GOLF CLUBS AND THE LIKE.

Application filed November 7, 1925. Serial No. 67,531.

This invention relates to improvements in shafts, particularly adapted, though not necessarily limited in its use for golf clubs, and one of the objects of the invention is to provide a shaft embodying a core and an improved outer shell of non-metallic composition of matter for the core, the portion of the casing or shell intermediate the head of the club and the handle grip being free from the core, whereby there will be created a certain free motion or action between the core and the outer shell or casing, with the result that the whipping action of the club will be greatly increased.

10 A further object is to provide an improved shaft of this character in which the outer shell or casing and the core will be fastened at the top or grip end of the shaft against relative rotary movement thereby producing

20 a golf club shaft having the proper stiffness and flexibility and at the same time the shaft will be provided with a maximum amount of torque.

25 A further object is to provide an improved shaft of this character embodying a tubular casing of non-metallic composition and a core which is telescoped into the casing, the tube and core being fastened together at both ends against relative rotary movement, the intermediate portions being free from each other whereby freedom of action of the shaft will be provided, the outer shell or casing by being fastened to the head of the club will produce the necessary torque and

35 at the same time will permit of the use of a rigid core in the construction of the shaft.

With such a construction the shaft will not only be strengthened and re-enforced, but the required flexibility of the shaft will not be interfered with and at the same time the shaft will be of the desired or required weight and rigidity.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a longitudinal sectional view of

the club end of a shaft constructed in accordance with the principles of this invention.

Figure 2 is a longitudinal sectional view 55 of the handle or grip end of the shaft.

Figure 2^a is a detail sectional view on line 2^a—2^a, Figure 2.

Figure 3 is a view similar to Figure 1 of the outer non-metallic casing or covering of the 60 shaft, showing the same secured to the head.

Figure 4 is a detail longitudinal sectional view of one end of a tubular metallic reinforcing core.

Figure 5 is a longitudinal sectional view 65 of the head end of another form of the invention.

Figure 6 is a horizontal sectional view taken on line 6—6, Figure 3.

Figure 7 is a transverse sectional view of 70 a solid re-enforcing core.

Figure 8 is an enlarged detail longitudinal sectional view showing one form of fastening for securing the re-enforcing core and casing together and for securing the casing to 75 the head of the club.

Figure 9 is a detail side elevation of two of the fastening members.

Figure 10 is a side elevation of another one of the fastening members.

Figure 11 is a side elevation of still another one of the fastening members.

Referring more particularly to the drawing the numeral 15 designates generally an outer tubular shell or casing of any desired 85 diameter and preferably of a tapered configuration. This casing is constructed of a non-metallic material, preferably a composition of matter known as pyroxyline, or of any other like material. One end of the casing 90 15 is telescoped into a head 16 of the club so that the lower extremity of the casing terminates within the head and is secured to the head in any desired or suitable manner such as by means of a suitable cement or fastening glue.

Telescoped into and encased within the casing 15 is a re-enforcing core 17 which is preferably tapered and tubular and constructed of metal.

The core 17 is secured to the casing 15 at the extremities thereof in any desired or suitable manner and the portions of the casing and core intermediate the securing means

are free from each other so as to permit of a certain free motion or action between the core and the outer casing or tube. At the grip or handle end of the shaft suitable fastening devices 18 may be provided such as pins or fastening rivets which pass transversely through slots 18' in the casing and core to permit of a relative longitudinal movement of the core and casing but will prevent a relative rotary movement thereof. The adjacent extremity of the core is preferably closed by means of a bumper element 19 secured in position in any suitable manner.

The other extremity of the core and casing are secured together in any desired or suitable manner and against relative rotary movement, preferably as follows. The lower extremity of the core 17 is closed as at 20 and is provided with an aperture 21 opening therein. The lower extremity of the casing 15 is preferably provided with spaced lugs or extensions 22 which are adapted to co-operate with corresponding lugs or projections 23 on an anchor member 24, the latter being provided with radially projecting teeth or ribs 25. The head of the club 16 is provided with an opening 26. This opening 26 is preferably provided with recesses 27 adapted to receive the ribs or projections 25 and thereby lock the element 24 against relative rotary movement with respect to the head 16. The element 24 is adapted to be inserted into the opening 26 so that the ribs or projections 25 will enter the recesses 27 and so that the lugs 23 thereon will interlock with the lugs 22 on the lower end of the casing 15. The lower extremity of the core 17 preferably terminates short of the lower extremity of the casing 15, and a fastening device 28, preferably in the form of a screw having left hand threads and a head 29 is provided for connecting the member or element 24 with the core 17. The body of the member 28 passes loosely through the element 24 and is threaded into the recess 21 in the end 20 of the core 17, the head 29 resting against the face of the element 24 so that when the element 28 is rotated it will be threaded into the opening 21 of the end 20 of the core 17 and there will be a tendency of the member 28 to impart a relatively longitudinal movement to the core 17 and casing 15 to draw the two together and cause them to be rigidly or firmly held with respect to each other. The left hand threads in the screw 18 and in the aperture 21 in the end 20 of the core 17 will have a tendency to tighten the screw and draw the core and casing together when the head 16 receives an impact, whereas if the threads were right hand threads such an action of the head would have a tendency to loosen the screw which is not desirable.

Threaded into the member 28 is a screw 30, the extremity 31 of which co-operates with

inclined faces 32 in the end of the member 28, the latter being split as at 33 to permit the same to be slightly expanded and thereby lock the member 28 in its adjusted position.

If desired a covering 34 of any suitable material may be provided on the grip end of the shaft.

In the form of the invention shown in Figures 4 and 5, the core 17 is telescoped into the casing 15 and the lower extremity of the core 17 is secured to the lower extremity of the casing 15 and both are secured to the head 16 of the club in any suitable manner, preferably by means of fastening devices 35 in the form of pins or rivets which pass through the head and through the core and casing, thereby preventing relative rotary movement of these parts.

In this form of the invention the recess 27 in the end of the club may be closed by a suitable plug 36.

In the form of the invention shown in Figure 7 the core 37 is of a solid construction such as wood and is adapted to be telescoped into and encased within the shell or casing 15 and the extremities of the core may be secured in a manner similar to the manner as described in connection with the form of the invention shown in Figure 5, or may be fastened within the head in any desired or suitable manner.

With this invention there is provided a golf club shaft having an outer tubular shell of non-metallic material which is loose or separate from the core intermediate the extremities of the shaft, the shell and core being fastened together at the extremity of the shaft and against relative rotary movement, with the result that there will be provided a shaft for golf clubs having the proper stiffness and flexibility and yet there will be provided a maximum amount of torque.

By reason of the fact that the outer shell or casing is free from the core intermediate the fastening means at the extremities of the core there will be created a certain free action or motion between the core and the outer tube or casing. If the casing and core are secured together intermediate the extremities, or the fastening means at the extremities, there would not be produced the free flexible motion or action that is necessary in a golf club, with the result that the whipping action of the club would be impaired, but by maintaining the core and casing detached from each other intermediate the fastening means, the whipping action of the shaft will be increased and at the same time the necessary torque will be created and it will be possible to employ a rigid core.

While the preferred forms of the invention have been herein shown and described, it is to be understood that various changes may be made in the details of construction and in the combination and arrangement of

the several parts, within the scope of the claims, without departing from the spirit of this invention.

What is claimed as new is:—

5. 1. A shaft for golf clubs embodying a tubular non-metallic casing, a core telescoped into and fitting within the casing, and means securing the ends of the core and casing together, the portions of the core and casing intermediate the said securing means being free for slight relative movement. 50
10. 2. A shaft for golf clubs embodying a tubular non-metallic casing, a core telescoped into and fitting within the casing, and means 55 securing the ends of the core and casing together, the portions of the core and casing intermediate the said securing means being free for slight relative movement. 60
15. 3. A shaft for golf clubs embodying a tubular non-metallic casing, a hollow metallic core telescoped into and fitting within the casing, and means securing the ends of the core and casing together, the portions of the core and casing intermediate the said securing means being free for slight relative rotary movement. 65
20. 4. A shaft for golf clubs embodying a tubular non-metallic casing, a hollow metallic core telescoped into and fitting within the casing, and means securing the ends of the core and casing together, the portions of the core and casing intermediate the said securing means being free for slight relative movement. 70
25. 5. A shaft for golf clubs embodying a tubular non-metallic casing, a hollow metallic core telescoped into and fitting within the casing, and means securing the ends of the core and casing together, the portions of the core and casing intermediate the said securing means being free for slight relative rotary movement. 75
30. 6. A shaft for golf clubs embodying a tapering tubular non-metallic casing, a tapering core telescoped into and fitting within the core, and co-operating means disposed at one end of the casing and core for securing the two together, the said means adapted to impart a relative longitudinal movement to the casing and core. 80
35. 7. A shaft for golf clubs embodying a tapering tubular non-metallic casing, a hollow metallic tapering core telescoped into and fitting within the core, and co-operating means disposed at one end of the casing and core for securing the two together, the said means adapted to impart a relative longitudinal movement to the casing and core. 85
40. 8. A shaft for golf clubs embodying a tapering tubular non-metallic casing, a hollow metallic tapering core telescoped into and fitting within the core, a head secured to the said casing and into which head the casing and core telescope, and co-operating means disposed at one end of the casing and core for securing the two together, the said means adapted to impart a relative longitudinal movement to the casing and core. 90
45. 9. A shaft for golf clubs embodying a tubular tapering non-metallic casing, a tapering core telescoped into and fitting within the casing, means securing the extremities of the casing and core together, the portion of the core intermediate the said securing means being free for slight relative movement, and a head into which one end of the casing and core telescope, the last recited end of the said casing being secured to said head. 95
10. 10. A shaft for golf clubs embodying a tubular tapering non-metallic casing, a hollow metallic tapering core telescoped into and fitting within the casing, means securing the extremities of the casing and core together, the portion of the core intermediate the said securing means being free for slight relative movement, and a head into which one end of the casing and core telescope, the last recited end of the said casing being secured to said head.
- In testimony whereof I have signed my name to this specification, on this 4th day of November, A. D. 1925.

HAROLD G. BARRETT.
